PHOTOFASL CASING

Raymond Le Roy Kreidler, Bloomfield, N. J., assignor to Westinghouse Electric & Manufacturing Company, East Pittsburgh, Pa., a corporation of Pennsylvania

Application May 14, 1941, Serial No. 393,320

5 Claims.

(Cl. 67—31)

My invention relates to photoflash lamps, and particularly to photoflash lamps having a casing of a plastic material.

An object of my invention is to provide a flash lamp of an organic plastic having efficient light output.

Another object of my invention is to provide a casing of an organic plastic capable of containing an active gas at more than atmospheric pressure.

Another object of my invention is to provide an easily assembled photoflash lamp of an organic plastic casing not requiring the application of high temperature.

Other objects and advantages of the invention will become apparent from the following description and drawing in which:

Figure 1 is a front elevation of a preferred embodiment of my invention substantially to its preferred actual scale.

Figure 2 is a cross sectional view on a much larger scale.

Figure 3 is a cross sectional view on lines III—III of Figure 2.

Figure 4 is an enlarged detail view of the interlocking joint between the bulb and base in Figure 2.

Figure 5 is a cross sectional view illustrating the sealing of one of the conductors in Figure 2.

Figure 6 is a view on lines VI—VI of Figure 2 prior to the cutting off of the exhaust tube.

Figure 7 is a cross sectional view of a modification of the base of Figure 2.

My invention constitutes an improvement over the invention of a photoflash lamp which is disclosed in the copending application of Michael D. Margitta, filed January 26, 1940, Serial No. 315,738.

My invention eliminates completely the problem of broken glass in connection with the transportation, utilization and disposal of photoflash lamps by my choice of a plastic material. The preferred construction of my photoflash lamp also eliminates the necessity of high temperatures during assemblage of the device. My invention also has the advantage that it permits the utilization of oxygen inside of a photoflash lamp at greater than atmospheric pressure. With glass casing lamps at the prior art, there would be danger of flying particles of glass from the possibility of explosion as the result of the greater pressure of gas therein.

In Figure 1 I have disclosed an elevational view of my photoflash lamp in its preferred actual size. The structure of this photoflash lamp is more clearly disclosed in Figure 2. The bulb portion 10 is preferably a closed end cylinder of an organic plastic translucent to light and preferably translucent enough to be substantially transparent. I prefer to mold this bulb portion of ap-

proximately 40 mil material as this is thin enough to be self-supporting and yet thick enough to mold properly.

The preferred material is that of cellulose acetate although vinyl compounds, butyrates, methacrylates and similar materials may be used. This cylindrical portion preferably has a curved closed end 11. The base portion 12 of the lamp is preferably of the same material and is dish-shaped having an upper edge 13 with a recessed portion 14 to receive the edge 15 of the bulb portion 10. The bulb portion 10 preferably has a slight rounded rim 16 on its periphery near the edge 15 and this projecting rim 16 is adapted to be forced into locking engagement with a corresponding groove 17 on the inner face of the recess 14 by the slight resiliency of the cellulose acetate wall 10. The interlocking joint between the bulb edge 15 and the base rim 16 under the compressed bulb edge 15 has a mechanical strength to prevent separation of the two portions under any increased pressure during flashing operations.

The base has preferably a central depressed portion 20, from which extends a central tubulation 21 for the purpose of exhausting and filling the tube with an active gas such as oxygen. The lamp has two connections or standards 22 and 23, preferably of copper and bound in spaced relationship with each other by a bead of insulation 24 which may be of glass or ceramic material, a tungsten filament 25, and, preferably attached thereto, igniting means 26 and 27 formed by dipping the conductors and filament into a nitro-cellulose binder containing powdered zirconium, magnesium and potassium perchlorate.

The conductors 22 and 23 where they pass through the base are preferably flattened as indicated at 28 in Figures 2 and 5. The base has two integral tubular projections 29 surrounding this flattened portion of the conductors. The conductors are sealed to the projecting portions 29 by having two preferably slightly heated flat metal surfaces 30 and 31, pinch the cellulose acetate projection 29 about the flattened surface 28 of the conductors, as illustrated in Figures 5 and 6.

The inner surface of the bulb and preferably also the base, is sprayed with a coating 32 of a transparent inorganic material that will not readily combine with oxygen at instantaneous high temperatures.

The material which we have found most suitable is that of sodium silicate. Other transparent inorganics that might be used are those sold under the trade names of "Abapon" and "Stacol." The interior of the bulb is then filled with a combustible metal, such as aluminum or magnesium wire 33. I prefer to use finely chopped aluminum foil having a cross sectional area of 1 mil square.

The bulb portion is then forced over the base

and interlocked by the rim 18 and groove 17. A suitable cement 34 is then placed at the adjoining edges of the bulb and base portions, and this cement may be covered in turn if it is desired, by an additional lacquer coating 35. The interlocking joint takes all the strain and leaves to the cement and lacquer the sole job of making the joint vacuum tight. The atmosphere is then removed from the lamp through the tubulation 21 and replaced with an active combustion supporting gas such as oxygen.

I prefer to insert oxygen at distinctly more than atmospheric pressure, and have found that a pressure of 120 to 150% of atmospheric pressure produces a satisfactory flash in combination with the combustible metal and igniting means. In case higher pressures are desired, I increase the wall thickness of the bulb up to 100 mils or more.

The tubulation 21 is then sealed off by two more metal surfaces similar to 30 and 31, and the excess tubulation cut off by the knives 36, as illustrated in Figure 6. A suitable socket connection can then be applied to the lamp. As disclosed in Figure 2, a cylindrical casing 40 of brass fits tightly over the base projection 20 after one of the conducting standards 22 has its end bent over between the projecting base 20 and the metal wall 40.

The overlapping tip 41 of this connection is soldered to the outer wall of the cylindrical casing. The other end 42 of the other connecting wire 23 extends to a metal contact cap 43 embedded in insulation 44 in an opening at the bottom of the metal casing 40. The metal casing 40 may have the projecting lugs 45 for retaining the lamp in its socket until flashed.

If desired screw threads may be placed in the metal casing 40 if a screw threaded socket is to be utilized. Other types of socket connections can also be provided, as illustrated in Figure 7, where one of the connecting standards 46 passes through the bottom projecting tube 47 used for tubulation and then sealed off at 48.

The wire is secured to a metal cap 49 at the top end of the sealed off tubulation 47. The other connection or standard 50 passes through the casing to one side of the central tubulation 47 and is attached to a conductive band 51 surrounding the tubulation 47. Various other types of connections can obviously be made to the igniting means in the interior of the lamp.

When photoflash lamps, utilizing an organic plastic as a casing, were utilized, the heat sometimes concentrated near the plastic casing with a resulting volatilization of some of the organic constituents of the plastic envelope. These volatile compounds burn in the oxygen atmosphere, thereby reducing the oxygen available for burning the aluminum or magnesium metal in the lamp. These volatile organic compounds would then break down with a resulting heavy deposit of carbon on the inside of the envelope. The deposit of carbon, of course, tended to reduce the light output of the lamp.

My inside coating of a transparent inorganic material, such as sodium silicate, acts as a heat insulator, preventing the burning metal from coming into direct contact with the organic plastic material of the envelope. The complete combustion of the aluminum or magnesium charge of the photoflash lamp is, accordingly, permitted with a corresponding increase in light output. This coating, while preferably sprayed on the surface, can also be placed thereon by flushing

a solution of sodium silicate on the surface and then permitting it to dry.

It is apparent that many modifications may be made in my invention and, accordingly, I desire only such limitations to be imposed thereon as is necessitated by the spirit and scope of the following claims.

I claim:

1. A photoflash lamp casing subject to severe internal explosive pressure in use and comprising a base portion and a bulb portion of translucent organic plastic of a thickness to be self-supporting and an interlocking joint between said base and bulb portion, the edge of said bulb portion being compressed within said base portion and thereby obtaining increased retentive grip between the bulb portion and base portion with increase of pressure within the lamp in excess of external pressure.
2. A photoflash lamp casing subject to severe internal explosive pressure in use and comprising a translucent plastic bulb portion, and a base portion having a rim overlapping the edge of said bulb portion, said base portion having an interior peripheral groove therein and the bulb portion having a peripheral bead facing said groove and forming an interlocking joint therewith and thereby obtaining increased retentive grip of the interlocking joint with increase of pressure within the lamp in excess of external pressure.
3. A photoflash lamp casing subject to severe internal explosive pressure in use and comprising a translucent plastic bulb portion, a base portion having a rim overlapping the edge of said bulb portion, said base portion having an interior peripheral groove therein and the bulb portion having a peripheral bead facing said groove and forming an interlocking joint therewith and thereby obtaining increased retentive grip of the interlocking joint with increase of pressure within the lamp in excess of external pressure, and cement between and at the exterior of said rim and edge thereby sealing the joint to admission of air to the bulb while the internal pressure is less than external pressure.
4. In a lamp provided with a radiation-permeable envelope having a neck of material of the character of organic plastic depending therefrom, a base secured on said neck and providing space between the bottom of the neck and bottom of the base, lead-in support wires for a filament extending through the bottom of said base and having flattened areas in the portion thereof where passing through the plastic material, and pressure-sealed thereto by pressure applied normal to the flattened areas thereby obtaining intimate and tight sealing engagement of the plastic on the lead-in wires.
5. In a lamp provided with a radiation-permeable envelope having a neck of material of the character of organic plastic depending therefrom, a base secured on said neck and providing space between the bottom of the neck and bottom of the base, lead-in support wires for a filament extending through the bottom of said base and having flattened areas in the portion thereof where passing through the plastic material, the bottom of said neck having nipples thereon surrounding the said flattened areas of the lead-in wires, and pressure-sealed thereto by pressure applied normal to the flattened areas thereby obtaining intimate and tight sealing engagement of the plastic on the lead-in wires.

RAYMOND LE ROY KREIDLER.
